Primary Examiner — Catherine Tuttle(74) *Attorney, Agent, or Firm* — Sterne Kessler Goldstein & Fox P.L.C.(57) **CLAIM**

The ornamental design for a display apparatus, as shown and described.

DESCRIPTION

FIG. 1 is a front perspective view of a display apparatus showing our new design;

FIG. 2 is a top view thereof;

FIG. 3 is a bottom view thereof;

FIG. 4 is a front view thereof;

FIG. 5 is a rear view thereof;

FIG. 6 is left side view thereof; and,

FIG. 7 is a right side view thereof.

The dot dashed broken lines show unclaimed boundaries which form no part of the claimed design. The oblique shade lines show transparency and not surface ornamentation.
